UNITED STATES PATENT OFFICE

168,922

VOLT-OHM METER

Leslie M. Balter, Rutherford, N. J.

Application June 18, 1952, Serial No. 20,250

Term of patent 7 years

(Cl. D26—1)

To all whom it may concern:

Be it known that I, Leslie M. Balter, a citizen of the United States, residing at Rutherford, State of New Jersey, have invented a new, original, and ornamental Design for a Volt-Ohm Meter, of which the following is a specification, reference being had to the accompanying drawing, forming a part hereof.

Figure 1 is a side view of a volt-ohm meter showing my new design.

Figure 2 is a rear view thereof; and

Figure 3 is a front view thereof.

I claim:

The ornamental design for a volt-ohm meter, substantially as shown.

LESLIE M. BALTER.
